UNITED STATES PATENT OFFICE.

BURNIE A. STAMP, OF NORTH BRADDOCK, PENNSYLVANIA.

SHIPPING-CRATE.

1,362,645.

Specification of Letters Patent. Patented Dec. 21, 1920.

Application filed March 6, 1919. Serial No. 280,921.

To all whom it may concern:

Be it known that I, BURNIE A. STAMP, a citizen of the United States, residing at North Braddock, in the county of Allegheny and State of Pennsylvania, have invented certain new and useful Improvements in Shipping-Crates, of which the following is a specification.

My invention relates to knock-down shipping crates. Crates embodying my invention are particularly well adapted for the shipment of chickens and other birds, although they are not limited to this particular use.

One object of my invention is the provision of a knock-down crate which is rugged in construction, yet which occupies the smallest possible amount of space when folded.

I will describe one form of crate embodying my invention, and will then point out the novel features thereof in claims.

In the accompanying drawings, Figure 1 is a view showing in side elevation one form of crate embodying my invention. Fig. 2 is a view showing the crate illustrated in Fig. 1 but looking at the latter from the right-hand side. Fig. 3 is a sectional view taken on the line III—III of Fig. 1 and looking in the direction indicated by the arrows. Fig. 4 is a sectional view taken on the line IV—IV of Fig. 2 and looking in the direction indicated by the arrows. Fig. 5 is a top plan view of the crate shown in Figs. 1 and 2. Fig. 6 is a view showing in end elevation a hasp 14 used in locking the crate shown in the preceding views. Fig. 7 is a sectional view taken on the line VII—VII of Fig. 5, and showing in detail the locking device of which the hasp 14 forms a part. Fig. 8 is a view showing in front elevation the device shown in Fig. 5 for latching the door E in the closed position, the shield 22 being removed. Figs. 9 and 10 are views showing in front and top elevation, respectively, a device which may be employed for locking the door E in closed position.

Similar reference characters refer to similar parts in each of the several views.

Referring now to the drawings, the crate comprises a bottom member A, two oppositely disposed side members B and B^a, two other oppositely disposed side members C and C^a, and a top member D.

The bottom member A is preferably a flat piece of wood, whereas each of the side

members, as here shown, comprises a rectangular frame 2 provided with a number of bars or slats 3. The top member D is of special construction, as will be explained 60 hereinafter.

The two side members B and B^a are attached by hinges H to cleats 5 and 5^a, respectively, which cleats are mounted on the upper surface of the bottom member A. 65 Each of the hinges H is formed (see Fig. 3) by cutting away the cleat 5 except for a centrally disposed pin 6, and passing around this pin a strap 7 of sheet metal the ends of which are attached by screws 8 to 70 a recess in the surface of frame 2. The height of each cleat 5, and the location of the pin 6 are such that when the side members B and B^a are swung inwardly they lie flat against the bottom member A. 75

The two side members C and C^a are attached to cleats 4 and 4^a by hinges H' which are similar to hinges H. These cleats are higher than cleats 5 and 5^a, however, and are of such height that when the side members B and B^a are folded down against the bottom member, the side members C and C^a may likewise be swung inwardly and will lie flat against members B and B^a. 80

The top member D is hinged and slidably attached to the side member C by means which I will now explain, referring particularly to Figs. 2 and 4. The cleat 4 is provided with two notches 10 to accommodate two straps 9, each of which is shaped 90 as shown in Fig. 4. The lower end of each strap passes horizontally through notch 10 and is bent upwardly at its end so that it can be attached by screws 12 to the inner side of the lower strut of the frame of side member C. The upper end of the strap passes horizontally through a slot 11 in the frame of top member D, and is then bent downwardly and attached to the inner face of the frame of side member C by screws 12^a. It will be seen that by virtue of this construction the top member D can be swung 95 upwardly so that it is parallel to side member C, and can then be slid downwardly or telescoped with respect to member C. 100

The manipulation of the parts of the crate thus far described, is as follows: To fold the crate, the top member D is first swung upwardly and then slid straight down on the straps 9 so that it is parallel with 110 and lies flat against side member C. The side members B and B^a are then folded in-

wardly until they rest against the bottom member A. The next step is to fold member C^a inwardly so that it rests on top of members B and B^a, and the last step is to 5 fold the side member C inwardly, carrying with it the top D, so that member C rests on top of members B and B^a. The top member D then rests flat against members C and C^a, and covers no more area than does the 10 bottom member A.

The crate is opened by a sequence of operations which will be self-evident from the foregoing.

To prevent the crate from collapsing accidentally while in the set-up condition, the 15 side members are provided with a number of ears 13. Two of these ears are attached to the two ends respectively of each side member C and C^a, as shown in Fig. 1, and 20 project into the path of members B and B^a to prevent the latter members from being swung out beyond vertical positions with respect to the bottom member A. Each side member B and B^a is provided with similar 25 ears 13^a which project into the path of the top member D and so prevent these side members from swinging inwardly from the vertical positions. It will be seen, therefore, 30 that the ears thus far referred to serve to lock the side members B and B^a in vertical positions. It remains only to prevent the side member C^a from swinging outwardly beyond the vertical position, and this is accomplished by ears 13^b attached to the inner 35 surface of the frame of this member, as shown in Fig. 1.

Any suitable means may be provided for 40 clasping the top member D to the side member C^a when the crate is set up. As here shown, this means comprises a hasp 14 and an eyelet 15. As shown in Figs. 5 and 6, the hasp 14 is hinged to the top member D and is provided with a slot 14^a. One corner of the projecting end of the hasp is bent 45 outwardly at right angles as shown at 14^b, and this corner is provided with a hole 14^c. The eyelet 15 is formed as shown in Fig. 7, and comprises a piece of wire passing through a hole in the frame of the side 50 member C^a. The two ends of this eyelet are bent at right angles to the middle portion, and the end having the eye is on the outside of member C^a. To clasp the top member to the side member, the eyelet is turned 55 so that the outer end is in a vertical position, the hasp 14 is then swung downwardly so that the eye projects through slot 14^a, and finally the eyelet is swung around until the eye rests against the upturned corner 60 14^b. The eye then registers with hole 14^c, so that the crate can be sealed, if desired, by passing an ordinary wire seal through the eye and the hole 14^c.

In order to clasp the crate when in 65 knocked-down condition, the cleat 4^a is pro-

vided with a second eyelet 15^a (see Fig. 1) which registers with the hasp 14 when the crate is folded, and which co-operates with the hasp in the same manner as eyelet 15.

When a knock-down crate is used for the 70 transportation of chickens or other birds, it is desirable that means be provided for removing and inserting the birds without fully opening the crate. For this reason, I preferably provide the top member D with 75 a door E, as shown in Fig. 5. Referring to this view, the top member comprises a frame 2, and is provided with cross struts 17 and 17^a which form a rectangular opening in the center. The door E fits in this opening, 80 and comprises a frame 2^a which is attached to one of the cross struts by hinges 19. The frame 2^a carries two fixed slats 3^a, and a third slat 3^b which is pivotally mounted in the frame at 16. This pivoted slat passes 85 through a slot 18 in the door frame, and cooperates with a slot 21 in the cross strut 17^a, which slot is shaped as shown in Fig. 8. When the door is closed, the slat 3^b is at the inner or closed end of slot 21 as shown 90 in Fig. 8, being biased to this position by a spring 20. To open the door, the pivoted slat is swung to the right so that it passes out of the open end of slot 21. The door is closed and latched by a reverse operation. 95

The slat 3^b may be secured in the latching position, if desired, by the device shown in Figs. 9 and 10. This device comprises a shield 22 pivotally mounted at 22^a on the strut 17^a and having a slot 22^b which receives the free end of slat 3^b. This shield also has an outwardly bent ear 22^c which seats against a member 23 attached to and projecting from the under side of the strut 17^a. The ear 22^c and member 23 are provided with registering holes through which a wire seal may be passed. The door may, of course, be opened by swinging the shield upwardly around its pivotal point, and may be locked in closed position by the reverse 110 operation.

Although I have herein shown and described only one form of crate embodying my invention, it is understood that various changes and modifications may be made 115 therein within the scope of the appended claims without departing from the spirit and scope of my invention.

Having thus described my invention, what I claim is:

1. A poultry crate having a door in one wall, said door comprising a frame carrying a plurality of slats, one of said slats being pivotally mounted in one side of the frame and projecting through a slot in the 125 opposite side, a notch in the body of the crate registering with said slot and adapted to receive said pivoted slat to latch the door in closed position, and a spring biasing said slat to latching position.

2. A poultry crate having a door in one wall, said door comprising a frame carrying a plurality of slats, one of said slats being pivotally mounted in one side of the
5 frame and projecting through a slot in the opposite side, a notch in the body of the crate registering with said slot and adapted to receive said pivoted slat to latch the door in closed position, a spring biasing said slat
10 to latching position, and a shield pivotally

attached to the body of said crate for retaining said pivoted slat in latching position.

In testimony whereof I affix my signature in presence of two witnesses.

BURNIE A. STAMP.
